Des. 203,780
Patented Feb. 15, 1966

203,780

FOLDING BOAT PROPELLER

David W. Beck, Lakewood, Calif., assignor to Aerolab
Development Co., Monrovia, Calif., a corporation of
California

Filed May 20, 1965, Ser. No. 85,375

Term of patent 14 years

(Cl. D71—1)

FIG. 1

FIG. 2

FIG. 3

FIG. 4

FIG. 5

FIG. 6

FIG. 7

FIG. 8

FIGURE 1 is a perspective view of a folding boat propeller embodying my new design with the blades of such propeller being disclosed in a folded position;

FIGURE 2 is a view similar to FIGURE 1 but showing the blades in an extended position;

FIGURE 3 is a side elevational view of my propeller with the blades thereof in a folded position;

FIGURE 4 is a view similar to FIGURE 3 but showing the blades in an extended position;

FIGURE 5 is a rear view of my propeller with the blades in a folded position;

FIGURE 6 is a view similar to FIGURE 5 but showing the blades in an extended condition;

FIGURE 7 is a front view of my propeller showing the blades in an extended condition; and

FIGURE 8 is a view similar to FIGURE 7 but showing the blades in a folded position.

I claim:

The ornamental design for a folding boat propeller, substantially as shown and described.
